DESIGN FOR A CURTAIN FABRIC

Joseph Meyer, New York, N. Y.

Application August 20, 1935, Serial No. 58,213

Term of patent 7 years

To all whom it may concern:

Be it known that I, Joseph Meyer, a citizen of the United States, residing at New York, in the county and State of New York, have invented a new, original, and ornamental Design for a Curtain Fabric, of which the following is a specification, reference being had to the accompanying drawing, forming part thereof.

The figure is a plan view of a curtain fabric showing my new design.

I claim:

The ornamental design for a curtain fabric, as shown.

In testimony whereof, I affix my signature.

JOSEPH MEYER.
